UNITED STATES PATENT OFFICE.

RICHARD MORRISON AND JOHN DYER, OF SALT LAKE CITY, UTAH TERRITORY.

WATER-CLOSET TANK.

SPECIFICATION forming part of Letters Patent No. 538,339, dated April 30, 1895.

Application filed March 6, 1893. Serial No. 464,925. (No model.)

To all whom it may concern:

Be it known that we, RICHARD MORRISON and JOHN DYER, citizens of the United States, residing at Salt Lake City, in the county of 5 Salt Lake and Territory of Utah, have invented and produced a new and useful Improvement in Water-Closet Tanks, called the "Morrison & Dyer tank," of which the following is a specification.

- 10 to This invention relates to tanks for flushing closets; and aims to provide a means for varying the level of the water in the flushing tank to meet any requirement, and obviate the noise incident to flushing closets in general use.
- 15 15 With these ends in view and such others as appertain to the invention the improvement consists of the novel features hereinafter more fully described and claimed, and shown in the annexed drawings, in which—
- 20 20 Figure 1 is a front view of a tank embodying the invention, part of the same being broken away and the inner cylinder, supply and discharge pipes, and the tube for controlling the level of the water being shown in section. Fig. 2 is a top plan view of the tank. Fig. 3 is a bottom view of the tube for controlling the water level, showing the valve and the valve guard on a larger scale. Fig. 4 is a front view on a larger scale of the guide 25 30 through which the rod carrying the valves operates. Fig. 5 is a cross section of the complete guide and valve operating rod on the line 5—5 of Figs. 1 and 5 on the same scale as Fig. 4.
- 35 35 The tank Z is closed and may be of any approved form and design to meet the requirement of the trade. As shown it is semi-cylindrical in cross section and provided with apertured ears or lugs z by means of which it is secured to a suitable support. A receptacle or vessel C is located within the tank and is connected with the top thereof by means of a cap D which screws into the said top of the tank. This receptacle C is tubular and is 40 45 provided at its lower end with a contracted portion C' terminating in a valve seat c on the inner side. The supply pipe A connects with the cap D. A pipe B located within the tubular receptacle C connects at its upper 50 end with the cap D and forms a continuation

or prolongation of the pipe A and is perforated at its lower end, which end is closed by a cap b.

A pipe R adjustable in the upper head of the tank, constitutes a regulator to control 55 and govern the level of the water in the tank. This pipe R works through a stuffing box E on the head of the tank by which a tight joint is obtained and the said pipe held in the required position. The lower end of this pipe 60 R forms a seat for a ball valve G which closes upwardly against the same and is retained in place by a guard or basket g. A ring F internally threaded, screws on the lower end of the pipe R and has the guard or basket attached. The valve G is a float valve and closes against its seat by the rising of the water in the tank thereby shutting off the ingress of air.

The flush pipe O is attached at its upper 70 end to the bottom of the tank by means of the ogee pipe M and a union or coupling composed of the oppositely flared parts K and L. The part K has a valve seat k which is closed by a valve I. The rod H is operated from the 75 closet in any of the well known ways and has the valves Y and I attached thereto by being confined between pairs of nuts, or in any desired manner. The valve Y closes down on the seat c and the valve I up against the seat 80 k. This rod H extends through a gland N at the lower side of the offset in the ogee pipe M and works through a guide S. This guide S is composed of a base X having grooved rollers T, and a cap J. The base and cap have 85 lateral flanges which are apertured to receive fastenings by means of which the said cap and the base are secured together and to a suitable support.

The operation of the device is as follows: 90 When using the closet the valve I is seated and closes the flush pipe. When required the rod H is operated to unseat valve I and seat valve Y. This operation causes the water to discharge from the tank through the flush pipe 95 and flush the closet in the ordinary manner. While the water is discharging from the tank the receptacle C is receiving a supply from the pipe B. When the rod H is actuated to seat the valve I the valve Y is unseated and 100

permits the water to pass from the receptacle C to the tank Z until the level of the water therein reaches the plane of the lower end of the pipe R and closes the same and shuts off the supply of air. The space above the water line W is an air chamber and as soon as the tension on the air confined therein equalizes the pressure of the water in the supply pipe the inflow of the water will cease. Obviously, by moving the pipe R up or down the water level can be changed at will to regulate the quantity of water in the tank.

Having thus described our invention, what we claim, and desire to secure by Letters Patent, is—

1. The combination with a closed flushing tank, of a chamber arranged within the same and provided with a valve seat at its bottom, the water supply pipe extending into said chamber, a discharge pipe extending from the tank and provided also with a valve seat a valve stem passing through said pipe into the chamber within the tank, said stem carrying two valves, the lower one being adapted to close up against the seat and the upper valve to close down upon its seat whereby when the tank is discharged the water from the

supply pipe will accumulate in the chamber and thus prevent noise, substantially as shown and described.

2. The combination with a tank of the adjustable air pipe provided with a cage or basket and ball valve, to regulate the height of the water within the tank, an inner chamber contracted at its lower end and formed with a valve seat, a supply pipe A, and continuation B extending into the chamber, said pipe B being closed at the bottom and provided with a series of perforations the discharge pipe curved in form and provided with a chamber at the top said chamber having a valve seat, a rod or stem H extending upwardly through the discharge pipe into the tank and inner chamber, said rod or stem carrying a valve Y within the inner chamber, and a valve I adapted to seat within the chamber of the discharge pipe, substantially as shown and described.

RICHARD MORRISON.
JOHN DYER.
